(57) **CLAIM**

The ornamental design for a motor housing for a lawn trimmer, as shown and described.

DESCRIPTION

FIG. 1 is a front perspective view of a motor housing for a lawn trimmer in accordance with our new design;

FIG. 2 is a rear perspective view of the motor housing for a lawn trimmer in accordance with our new design;

FIG. 3 is a front elevational view of the motor housing for a lawn trimmer in accordance with our new design;

FIG. 4 is a rear elevational view of the motor housing for a lawn trimmer in accordance with our new design;

FIG. 5 is a top plan view of the motor housing for a lawn trimmer in accordance with our new design;

FIG. 6 is a bottom plan view of the motor housing for a lawn trimmer in accordance with our new design;

FIG. 7 is a right side elevational view of the motor housing for a lawn trimmer in accordance with our new design;

FIG. 8 is a left side elevational view of the motor housing for a lawn trimmer in accordance with our new design; and,

FIG. 9 is a front perspective view of the motor housing for a lawn trimmer in accordance with our new design illustrating a state in which the motor housing is attached to other parts of the lawn trimmer.

The broken line showing of environment in FIGS. 2, 4, 5, 7 and 9 forms no part of the claimed design.
